UNITED STATES PATENT OFFICE.

JOHN B. NEIL, OF NEW YORK, N. Y., AND HUGH CHRISTIE, OF BOSTON, ASSIGNOR TO THE BIGELOW CARPET COMPANY, OF CLINTON, MASS.

DESIGN FOR A CARPET.

SPECIFICATION forming part of Design No. 12,442, dated August 30, 1881.

Application filed August 1, 1881. Term of patent 3½ years.

To all whom it may concern:

Be it known that we, JOHN B. NEIL, of New York, in the county and State of New York, and HUGH CHRISTIE, of Boston, in the county of Suffolk and State of Massachusetts, have invented a new and original Design for Carpet, of which the following is a specification.

This invention relates to a new and original design for carpets, oil-cloths, and similar fabrics; and it consists in the novel grouping and configuration of figures hereinafter more fully described.

The accompanying photograph illustrates a face view of a carpet having my new design.

15 a is a stripe containing rectangular figures set alongside one another, each figure being pointed at one end.

C is a stripe parallel to a, containing figures e, resembling the bricks in a wall, and leafy 20 sprays d at intervals.

i is a narrow stripe containing circular figures on a background of broken lines.

25 B is a stripe bordered on one side by the rectangular pattern q, and containing the ornamental vase-like figures f and c, with flowers projecting therefrom; also, the spray of oblong leaves b; also, the figure H, composed of a widely - opened rose - like figure, g, surrounded by large indented leaves, and having 30 projecting from it the figure h, a spray bearing leaves shaped like clover-leaves.

The figure O is a stripe bordering on the stripe H, and containing a series of overlapping half-circles, resembling a hedge.

We claim—

1. The design for a carpet, consisting of the stripe a, substantially as shown. 35
2. The design for a carpet, consisting of the stripe C, containing figures d and e, substantially as shown. 40
3. The design for a carpet, consisting of the stripe i, substantially as shown. 45
4. The design for a carpet, consisting of the figure H, substantially as shown. 50
5. The design for a carpet, consisting of the figures f and c, substantially as shown. 55
6. The design for a carpet, consisting of the figures H, h, and e, substantially as shown. 60
7. The design for a carpet, consisting of the stripe B, containing figures g h q b e f, substantially as shown. 65
8. The design for a carpet, consisting of stripes a C i, substantially as shown. 70
9. The design for a carpet, consisting of the stripe O, substantially as shown. 75
10. The design for a carpet, consisting of the stripes O, B, i, C, and a, substantially as shown. 80
